UNITED STATES PATENT OFFICE.

ERNST HAAF, OF DONAUESCHINGEN, GERMANY.

ELASTIC HEEL-PROTECTOR.

1,125,019.

Specification of Letters Patent.

Patented Jan. 12, 1915.

Application filed April 13, 1914. Serial No. 831,547.

To all whom it may concern:

Be it known that I, ERNST HAAF, a subject of the Emperor of Germany, residing at Donaueschingen, Baden, Germany, have invented a certain Elastic Heel-Protector, of which the following is a specification.

The present invention relates to a heel protector for boots and the like, and consists of a metal plate having raised edges forming a recess within which to accommodate an elastic pad. The plate is provided with apertures in which to guide a plurality of projecting studs forming the tread and having flat heads arranged between the plate and the elastic pad, the latter being disposed between the plate and the ordinary heel. The studs, while being thus capable of yielding resiliently under the weight of the user, protects the heel from wear and prevents slipping.

In the accompanying drawings the invention is illustrated, Figure 1 representing a view of the heel protector without the studs and as seen from the outside, Fig. 2, an inside view of the protector, Fig. 3, a cross-section of the protector as applied to the heel, Fig. 4, three views showing various forms of the studs, and Fig. 5, a plan and a cross-section of the elastic pad.

A metal plate 1, shaped like the heel and being preferably made of aluminium, is provided with raised edges forming a space within which an elastic pad 2, preferably made of rubber, is accommodated. The metal plate is provided with apertures in which to guide the shanks of a plurality of headed studs 3, the latter being held in posi-

tion by means of their heads which are flat and which are disposed between the pad 2 and the inner surface of the plate. The heel protector thus formed is applied to the heel 40 5, as shown in Fig. 3, so that the pad 2 faces the heel and is covered by the plate, both being secured in position by means of screws 4. The studs 3, which bear against the pad 2, project through the metal plate and take 45 the thrust as well as the wear. The pad 2, although covered up and protected from wear other than that caused by the action of the studs 3, yet produces the required resiliency. The studs, which can easily be replaced by fresh ones when worn out, may be provided with pointed, milled or rounded ends, as shown in Fig. 4, according to the 50 55 nature of the boot and to the purpose for which it is used.

I claim:—

A heel protector for boots and the like comprising a metal plate having apertures and having raised edges with which to bear 60 against the heel, an elastic pad accommodated within the space formed by said edges between the plate and the heel, and a plurality of headed studs guided in said apertures in said plate and projecting through the latter so as to take the thrust, the heads of said studs being arranged between the plate and the pad so as to bear against the latter, substantially as and for the purpose set forth. 65

ERNST HAAF.
